UNITED STATES PATENT OFFICE.

STEPHEN I. FEKETE AND STUART G. BAITS, OF DETROIT, MICHIGAN, ASSIGNEES TO
ESSEX MOTORS, OF DETROIT, MICHIGAN, A CORPORATION OF MICHIGAN.

INTERNAL-COMBUSTION ENGINE.

Application filed August 16, 1919. Serial No. 317,954.

To all whom it may concern:

Be it known that we, STEPHEN I. FEKETE, a subject of the King of Hungary, residing at Detroit, county of Wayne, State of Michigan, and STUART G. BAITS, a citizen of the United States, residing at Detroit, county of Wayne, State of Michigan, have invented a certain new and useful Improvement in Internal-Combustion Engines, of which the following is a specification, reference being had therein to the accompanying drawings.

Our invention relates to the cam drive of an internal combustion engine of the type shown and described in a companion application, Serial No. 318,832 filed August 20, 1919. In that application there is shown a four-cycle internal combustion engine having exhaust valves operated by a cam shaft located below the cylinders parallel with the crank shaft and inverted inlet valves operated directly by a cam shaft located on the top of the engine. This invention is intended particularly for use where high speeds are required, as for instance, in racing engines and in aviation work.

The present invention relates particularly to the mechanism for operating the overhead cam shaft from the exhaust cam shaft or crank shaft. As is well known to those skilled in the art, considerable difficulty has heretofore been experienced owing to the fact that the vertical expansion of the cylinder block or any uneven alignment of the cam shaft results in disturbing the relation of the driving gears to each other and consequently interferes with the best operation of the engine. The present invention, therefore, has for its object to provide mechanism for driving the overhead cam shaft which will not be affected by ordinary variations in the position of the overhead cam shaft regardless of the cause which produces them.

The invention will be fully understood from the following description when taken in connection with the accompanying drawings, and the novel features thereof will be pointed out and clearly defined in the claims at the close of this specification.

In the drawings, Fig. 1 is a vertical transverse section of an engine embodying our invention.

Fig. 2 is a vertical section of one end of the engine taken lengthwise of the cam shaft.

Fig. 3 is a section on line 3—3 of Fig. 2. 55

Referring now to the drawings, the cylinder is indicated at 11, the exhaust valve at 12 and the exhaust cam-shaft at 13. The inlet valve shown at 14 is inverted in the head 15 which is removably secured to the cylinder block 16. The inlet valve stem is shown at 17 and is acted upon by a tappet 18 operated by the cam 19 on the cam shaft 20. In the engine shown there are two inlet and two exhaust valves for each cylinder, and accordingly there are two inlet cams 19 for each cylinder. The cam shaft 20 is mounted in suitable bearings in the top of a housing 21. It will be seen that the distance from the inlet cam-shaft 20 to the bed 70 4 of the engine is considerable, and therefore that the expansion of the cylinder block, the removable head and the housing 21 will disturb the relation between the parts. To prevent this, we provide the following 75 mechanism:

On the end of the inlet cam-shaft 20 is a spider 23 having three arms at 120° from each other. (See Figure 3.) This spider 23 is secured to the end of the cam shaft in 80 some suitable manner, as for instance, by a key 24. Secured to the arms of the spider 23 are two rings 25 and 26 made of rubberized fabric having several plies of some suitable flexible material, having sufficient 85 strength for the purpose required. At 27 is shown a second spider having arms located midway between the arms of the other spider. Both spiders are secured by bolts or pins 321 to the said rubber disks 25 and 26. The spider 27 is provided with a sleeve 28 which has a bore 331 therethrough to receive the hub or sleeve 5 of a gear 31. The gear 31 is keyed to the spider 27, as shown at 3, and the sleeve 5 of said gear has a bore 90 6 which is considerably larger than that portion of the cam shaft 20 which passes through it, so that the angle of the cam shaft 20 relative to the gear 31 may be varied 95 slightly without any interference between the cam shaft and the gear. The sleeve 5 is mounted in bearings 29 and 30 in a frame member 36 which is itself secured to the engine bed 4 and is independent of the cylinder block, although it rests against it.

The gear 31 meshes with a gear 32 which is driven by a gear 33 which meshes with a gear 34. The gears 32 and 33 are mounted 100 105

on studs 7 which are secured to the frame member 36, as shown in Figure 2. The gear 34 is secured to the exhaust cam-shaft 13.

It will therefore be seen that there is an inverted universal joint between the cam shaft 20 and the gear 31, so that the variation in the position of the cam shaft will not affect the true running of the gear 31. Furthermore, since the gear 31 is supported on the member 36 which is separate from the cylinder block, the difficulties arising from uneven expansion are much lessened.

What we claim is:

1. In an internal combustion engine, a cylinder block, a cam shaft mounted on the cylinder block, a gear, a support for said gear independent of the block, a sleeve on which said gear is mounted having a central bore of greater diameter than the cam shaft 20 through which the cam shaft passes, and a universal joint connecting the sleeve and the cam shaft.
2. In an internal combustion engine, an engine cylinder having a valve, a cam shaft mounted on said cylinder for operating said valve, an actuating member for said cam shaft rotatable about the same axis as the said cam shaft and independent thereof, a

universal joint between the said member and the said cam shaft, and means independent of said cylinder to support the said actuating member.

3. In an internal combustion engine, an engine cylinder having a valve, a cam shaft mounted on said cylinder for operating said valve, an actuating member for said shaft independent thereof and mounted for rotation about the same axis as said cam shaft, said cam shaft extending through said member, a universal joint connecting said member and the end of said cam shaft, and means for supporting said member independently of said cylinder.

4. In an internal combustion engine, an engine cylinder having a valve, a cam shaft mounted on said cylinder for operating said valve, a universal joint on one end of said cam shaft, an actuating member being located between said universal joint and the cylinder, and means for supporting said member independently of said cylinder.

In testimony whereof we affix our signatures.

STEPHEN I. FEKETE.
STUART G. BAITS.
